DOOR HANDLE

Theodore H. Koeber, Oak Park, Ill., assignor to International Harvester Company, a corporation of New Jersey

Application April 3, 1951, Serial No. 14,702

Term of patent 7 years

(Cl. D10—8)

To all whom it may concern:

Be it known that I, Theodore H. Koeber, a citizen of the United States, residing at Oak Park, in the county of Cook and State of Illinois, have invented a new, original, and ornamental Design for a Door Handle, of which the following is a specification, reference being had to the accompanying drawings, forming part thereof, in which:

I claim:

The ornamental design for a door handle, as shown.

THEODORE H. KOEBER.
